(57) **CLAIM**

The ornamental design for the operating panel, as shown.

DESCRIPTION

FIG. 1 is a front elevation view of an operating panel showing my new design;

FIG. 2 is a rear elevation view thereof;

FIG. 3 is a perspective view thereof;

FIG. 4 is a left side elevation view thereof with the right side being a mirror image;

FIG. 5 is a top plan view thereof; and

FIG. 6 is a bottom plan view thereof.

FIG. 7 is a front elevation view of an another embodiment of the operating panel showing my new design;

FIG. 8 is a rear elevation view thereof;

FIG. 9 is a perspective view thereof;

FIG. 10 is a left side elevation view thereof with the right side being a mirror image;

FIG. 11 is a top plan view thereof; and,

FIG. 12 is a bottom plan view thereof.

The broken lines in the Figures show portions of the operating panel which form no part of the claimed design.
